Primary Examiner — Marie D. Fast Horse

(57) **CLAIM**

The ornamental design for a payment terminal with screen as shown and described.

DESCRIPTION

1.1 : Front

1.2 : Back

1.3 : Bottom

1.4 : Top

1.5 : Right

1.6 : Left

1.7 : Perspective

1.8 : Perspective

Payment terminal with screen.

The broken lines in the drawings depict portions of the payment terminal with screen that form no part of the claimed design.
